UNITED STATES PATENT OFFICE.

JUAN DIEGO SHAW, OF BUENOS AIRES, ARGENTINA.

SEWING-MACHINE.

1,300,496.

Specification of Letters Patent. Patented Apr. 15, 1919.

Application filed October 11, 1915. Serial No. 55,284.

To all whom it may concern:

Be it known that I, JUAN DIEGO SHAW, citizen of the Argentine Republic and resident of No. 870 Venezuela St., Buenos Aires, Argentina, have invented certain new and useful Improvements in Sewing-Machines, of which the following is a specification.

The present invention relates to improvements in sewing machines and refers in particular to machines adapted to be used for sewing and embroidering and one of its main objects is to provide for the operation of the machine being changed or set for embroidering, instead of sewing, for instance, with much less trouble than heretofore and without the necessity of dismounting any part of the machine, as is to be done in connection with the machines actually known.

A further object of the present invention is certain improvements in the stitch plate which, without materially adding to the cost of construction of the machine, will render the same more durable while eliminating at the same time the troubles caused by the repeated change of parts.

The main object of the invention consists in the provision of special means for suspending the operation of the feeder which causes the fabric to travel, as it is well known that when the machine is being used for embroidering, the fabric is to be moved by hand and it is therefore indispensable to stop the operation of the said feeder.

Other objects of the invention will appear in the course of the present specification and will be particularly pointed out in the final claims.

In order that the invention may be readily understood and carried into practice without difficulty, it has been illustrated by way of example in the accompanying drawings in which:

Figure 1 is a diagrammatical upper view of a sewing machine provided with the improvements according to the present invention.

Fig. 2 is an upper view, on a considerably enlarged scale, of the part of the machine which contains the stitch plate with the openings for the needle and the feeder teeth.

Fig. 3 is a sectional view on the dotted line A—B of Fig. 2.

Fig. 4 is a lower plan view of the machine, 55 showing the main operating parts of the same, as well as the particular devices for suspending the operation of the feeder.

Fig. 5 is an end view of the arrangement illustrated in Fig. 4. 60

Fig. 6 is a vertical view, partly in section, of the special device used to put in and out of gear the parts for transmitting motion to the feeder.

Fig. 7 is a vertical view, partly in section, 65 of the feeder teeth in their working position when the machine is being used for sewing, and

Fig. 8 is a similar view of said feeder in its inoperative position when the machine 70 is being used for embroidering, as will hereinafter be explained.

In all the said views, like numbers of reference indicate similar or corresponding parts. 75

The general construction and arrangement of sewing and embroidering machines being well known, it is deemed unnecessary to give here a detailed description of the same or of their manner of operating. This specification will therefore be restricted to the particular improvements applied to said machines in accordance with this invention, only referring to the general details of the machine when so required for the better 80 understanding of the description, and to this end the drawings illustrate a general construction of sewing machine, of the type well known as central bobbin machine, but I desire it to be understood that the invention 85 may as well be applied to any other kind of sewing machine, either partially or as a whole, or as regards its substantial features only. 90

The ordinary stitch plate, provided with the needle hole and the orifice which allows of the passage of the feeder teeth which cause the transport of the fabric and which in the machines actually known is screwed on the work plate of the same, being provided with one single opening for each purpose, is replaced in my improved machine, in accordance with this invention, by a circular plate 12, provided at its center with an open- 95
100

ing through which passes a screw 13 which when tightened, affixes said stitch plate 12 to the work plate or table 11 of the machine, in the manner clearly shown in Figs. 2 and 5 3 of the accompanying drawings.

The plate 12 is provided with a series of 10 borings or free spaces 15, of a shape corresponding to the feeder 18, each of said borings being provided with a special hole for 15 the passage of the needle. The said plate is also provided with a plurality of holes 17, exclusively destined for the passage of the needle. The free spaces 15 and the needle holes 16 are used only when sewing with the 20 machine and the operation of the feeder 18 is therefore indispensable for causing the transport of the fabric, but when the machine is being used for embroidering, the holes 17 are employed.

25 The free spaces 15 and the holes 16, as well as the needle passages 17, are arranged at equal distances from the center of the stitch plate, so that they will always register with the stroke of the needle, not shown in

30 The advantage which arises from the use of a plurality of needle holes in the same stitch plate will at once be recognized when considering that owing to the lateral deflections of the needle during work, caused mostly by vibrations which in practice are 35 unavoidable, said needle will gradually wear away the edge of the needle hole 16 or 17 (according to its use, for sewing or embroidery) until rendering the same useless. When this occurs in ordinary machines, the 40 stitch plate 12 must be removed from the machine and replaced by a new one, whereas in the improved apparatus according to this invention, all that is to be done is to loosen the screw 13 and turn the plate thereon as on an axle until one of the holes 16 or 17, according to the use, registers with the point corresponding to the passage of the needle.

45 For the purpose of facilitating the movement of the stitch plate which might cling fast to the adjacent parts owing to the lubricating oil or to dirt which may have gained 50 access to the parts, the screw 13 is rounded at its lower part, below the stitch plate 12, by a spring 14 which constantly tends to elevate the said plate and which of course, when the screw is loosened, will lift the plate so as to allow of the same being 55 readily turned on its axle.

As to the accurate positioning of the holes 16 or 17 in the point of passage of the needle might give rise to difficulties and loss of time if the operation had to be effected by guess, 60 the stitch plate 12 is provided at its outer periphery with a number of notches 19 the coincidence of each of which with a predetermined point corresponds to the registering of one of the holes 16 or 17 with the 65 point of passage of the needle of the ma-

chine. Said predetermined point might be marked by a line or in a similar manner and the notches on the periphery of the plate 12 might also be replaced by lines or other marks, but it is preferred to use notches as 70 these latter permit of the use of a special device for mechanically determining the exact position of the needle holes 16 or 17.

Said device consists of a small rod 20, provided at one of its ends with a nose 21, 75 adapted to enter into one of the notches 19 of the periphery of the plate 12, the end of the said rod being arranged exactly at the point of coincidence, as stated before. A coiled spring 22 placed on the said rod 20, 80 tends to keep the nose 21 of the rod constantly inserted in one of the notches 19. In order to withdraw the nose 21 of the rod from the notch, the rod 20 has been provided, at its opposite end, at the side of the 85 working plate 11 of the machine, with a button 23 which may be pulled out against the action of the spring 22, thereby allowing of the turning of the stitch plate to take place after loosening the screw 13. 90

After the plate has been placed in the desired position, the button 23 is released and the screw 13 is tightened, whereupon the machine is again ready for use.

Care is to be taken that when turning the 95 plate 12, the feeder teeth 18 are to occupy their lowest position, so as not to interfere with the movement of the plate, as will be understood, and for that purpose the fly wheel 24 of the machine is to be first turned 100 until the said teeth 18 assume the desired position.

When the machine is being used for sewing, the feeder teeth 18 are to receive their double reciprocal motion, to and fro and 105 upward and downward, as is well known in ordinary machines, said motion being generally realized by a double cam operated by a connection rod from the main shaft of the machine. 110

When the machine is being used for embroidering, such operation of the feeder teeth is to be suspended, as to the contrary the teeth would impact with the lower face of the stitch plate 12 causing the wear of 115 the teeth and the plate, thereby shortening the life of the machine and preventing its perfect operation.

As above stated, the motion of the feeder 120 is caused by double cam 25, 26 and the corresponding connections well known in the art, which need not be described here though the parts are shown in the accompanying drawings, for the better illustration of the invention. In accordance therewith, this set 125 of cams is freely mounted on the rock shaft 27 to which motion is imparted through 28 from the axle of the fly wheel 24 of the machine.

On the rock shaft 27 is keyed a piece 29 130

which when moved by the rod 31 operates the rod 30 for withdrawing the bobbin 32 at the moment desired. For this purpose, another plate 33 is arranged at the upper face 5 of the work plate or table of the machine, said plate 33 being affixed by means of hinges or screws, in the manner shown in the drawings.

The part 35 is also mounted idle on the 10 said rock shaft 27 and is provided with an annular groove 36 of convenient sectional shape, the purpose of which will be explained later on. The idle piece 35 is connected by means of the spline 34 to the piece 15 29, so that the latter will transmit its movement to the former, that is, the rock shaft will drive the part 35, by means of the aforementioned spline 34, without interfering with the sliding movement of the piece 35 20 on the shaft 27. The sliding piece 35 is provided on its face next to the cams 25—26, with a stud or pin 37, so that when said piece 35 is sliding on the shaft 27 toward the cams, the said stud 37 enters into the 25 recess 38 of the same and thereby transmits to the cams the motion of the rock shaft 27, in the ordinary manner, thereby causing the operation of the feeder 18, as usual in sewing machines.

30 The sliding movement of the sliding body 35 is brought about by means of a rod 39, provided at one of its ends with a stud or button 40 which protrudes from the table or work plate of the machine through a 35 suitable groove 41, the length of which determines the range of movement of the said rod. The other end of the rod 39 is bent at 42 and enters into the groove 36 of the sliding body 35 so that to the movement of 40 the said rod an equal amount of movement of the body 35 on the rock shaft 27 will correspond. The rod 39, the same as the rod 31, is provided with guiding supports or bearings 43, for a purpose which will be 45 readily understood.

When the machine is to be used for 50 embroidery, I first cause the disengagement of the piece 35, by pushing backward the stud or button 40, so that the cams 25—26 will be operated no more and the feeder teeth 18 will remain stationary at their lowermost position in which they will have been placed before, as has been explained.

55 The remaining parts of the machine do not differ from those commonly used. These parts may be of any other suitable type. The arrangement shown allows of the use of the rod 44 for regulating the length of the stitch as well as of any other means of 60 control heretofore used or which in the future may be used in connection with ordinary sewing machines.

As has already been explained, the fact of having the rod which supports the 65 pres- sure foot, constantly obstructing the view

when embroidering, constitutes a serious inconvenience and in order to eliminate the same, it is indispensable to be able to readily dismount the said support. For that purpose, the rod is made of two halves which 70 may be assembled together by any suitable means, so as to cause them to always remain in a predetermined position.

It will be evident that the present invention may be modified as regards the construction and arrangement of the parts described without however departing from the scope and substantial features of the invention which will be clearly pointed out in the final claims.

Thus, for instance, in lieu of using the plate 12 provided with five openings for sewing and five openings for embroidering, a plate provided with any suitable number of holes for sewing only, or with any suitable number of holes for embroidering only, might be employed, according to whether the machine is to serve for one or the other use; in such case, if the machine only is for sewing, the device for suspending the 90 operation of the feeder teeth might be eliminated, while when the machine only is to be used for embroidering, the entire feeding mechanism might be omitted. In the combined machines also the arrangement of said 95 holes may vary sometimes; for instance, the holes for sewing may be placed in one series and those destined for embroidering, in another, and the number of each kind of holes may be chosen as desired. In connection 100 with either modification, however, the coincidence of the notches or marks 19 on the periphery of the plate 12 are to be considered. Also other modifications might be introduced, as will readily occur to any person skilled in the art to which this invention belongs.

Having now particularly described and ascertained the nature of my said invention and in which manner the same is to be performed, I declare that what I claim is:

1. In a sewing machine, the combination with a rock shaft, feeder teeth, means actuatable to impart a double reciprocal movement to the feeder teeth, and rotary means 115 for actuating the means last mentioned, of means for clutching and unclutching the rotary means to and from the rock shaft; substantially as described.

2. In a sewing machine, the combination 120 with a rock shaft, feeder teeth, and means actuatable to impart a double reciprocal movement to the feeder teeth, of cams loosely mounted on the rock shaft for actuating the means last mentioned, and means for clutching and unclutching the cams to and from the rock shaft; substantially as described.

3. In a sewing machine, the combination 125 with a rock shaft, feeder teeth, and means actuatable to impart a double reciprocal move-

ment to the feeder teeth, of cams loosely mounted on the rock shaft for actuating the means last mentioned, the cams being secured together to rotate as one unit and said unit having a recess, a slide piece splined on the rock shaft, an offset stud on the slide piece, and a rod manually actuatable to insert the stud in the recess and to withdraw the

stud from the recess at will; substantially as described.

Signed at Buenos Aires, Argentina, this 14th day of September, A. D. 1915.

JUAN DIEGO SHAW.
